UNITED STATES PATENT OFFICE.

ARTHUR LEONARD WHEELDON, OF LONDON, ENGLAND.

FIGURE WHEELED TOY.

Application filed April 10, 1920. Serial No. 372,924.

To all whom it may concern:

Be it known that ARTHUR LEONARD WHEELDON, a subject of the King of Great Britain, residing at London, England, has 5 invented certain new and useful Improvements in Figure Wheeled Toys, of which the following is a specification.

The object of this invention is to construct a toy so that a doll, Teddy bear, or other like 10 puppet or effigy is combined with a wheeled vehicle or the like so as to give the appearance of the puppet or the like riding a scooter or like appliance.

For the purpose of this invention a 15 wheeled or other vehicle is constructed preferably from wire, the front of which may be provided with steering wheels or such vehicle may be provided with runners to form a sledge or coaster.

20 The Teddy bear or the like is provided with a clip or clips at the part to which it is to be connected to the vehicle or to an axle thereon so that it can be easily attached and removed therefrom.

25 The front of the vehicle has a rod pivotally connected to it which rod at its other end is connected pivotally or by a catch device to some part of the Teddy bear or the like so that such Teddy bear is held firmly 30 on the vehicle. The whole toy is movable about on its wheels and can be drawn along by a child by a piece of string attached to the vehicle.

The puppet can be made in almost any 35 position, say standing, sitting, kneeling or otherwise.

My invention is shown in simple form on the annexed drawings in which—

Figure 1 is a perspective elevation of a 40 complete device ready for being moved about.

Figure 2 is a similar view with the vehicle positioned ready for packing.

Figure 3 is a view of one of the feet and 45 showing a clip attached thereto.

Figure 4 is a perspective elevation of a frame in which the axle is cranked and to which crank the puppet is connected.

Figure 5 is a perspective elevation of the 50 front portion of the vehicle showing the front axle cranked to which crank the rod is connected.

The frame A of the vehicle is made of wire of oblong shape having curled portions 55 B on the narrow sides to receive axles C

carrying on their ends wheels D the axles C being kept in position by rings E secured thereto.

To the front a rod F is hinged.

A Teddy bear G is constructed with the 60 front paws H and arms I extended and the front paws H are connected by a bar J to which the free end of the rod F of the framework A is loosely but permanently connected.

One or both feet K of the Teddy bear G 65 is provided with spring clips L which can be pressed over the rear member of the frame A or on to the rear axle thereof and with the rod F hold the Teddy bear to the frame rigidly, or instead of connecting the Teddy 70 bear to the frame A I may connect it to a crank M of the rear axle C (Figure 4) or I may connect the rod F to a crank on the front axle C so that the Teddy bear G can be given a rocking motion during its travel 75 as will be understood.

The article is now complete and a string can be attached to the forepart.

For packing purposes the clips L are released from the frame A of the vehicle or 80 crank M of the axle and the frame A folded up to become positioned between the Teddy bear G and the rod F as at Figure 2 so that the whole is reduced to a much smaller compass.

What I do claim as my invention and desire to secure by Letters Patent, is:—

1. A toy consisting of a wheeled vehicle having a frame and a rod pivotally connected thereto, an axle for certain of the 90 wheels having a crank thereon, a figure permanently connected to the rod, and clips at one end of the figure for temporary connection to the crank or frame, whereby the figure may be placed in any one of a number 95 of positions.

2. A toy consisting of a wheeled vehicle having a rod pivotally connected thereto, and an axle provided with a crank, a figure permanently connected to the rod, and positioning clips on the figure for temporary connection to said crank or to some other part of the vehicle.

In testimony whereof I have hereunto set my hand in presence of two subscribing 105 witnesses.

ARTHUR LEONARD WHEELDON.

Witnesses:

H. MAYKEL,

FRED H. McAHEFF.
